FIG. 1

UNITED STATES PATENT OFFICE

2,684,210

WINDING MACHINE

John D. Conti, Elkins Park, Pa., assignor to American Viscose Corporation, Philadelphia, Pa., a corporation of Delaware

Application February 18, 1952, Serial No. 272,183

5 Claims. (Cl. 242—55)

1

This invention relates to a winding machine and particularly to a winding machine for simultaneously winding a plurality of strips, such as tapes, ribbons or the like.

In the winding of tapes, particularly following an operation upon the tapes, such as slitting, coating or the like, it has been the practice heretofore to drive a shaft upon which one or more winding cores are rotatably mounted in such a manner that friction means transmits the motion of the shaft to the winding core whereby rotation of the shaft at somewhat greater speed than the rate of delivery of the tape to the core effectuates the winding while tensioning the tape or tapes. In some of such systems, the shaft is driven at such a speed that regardless of the diameter of the windings on the take-up package, the linear peripheral speed would be at all times greater than the speed of delivery of the tape, such as from the slitting or other processing operation, except for the fact that the tension produced in the tape or tapes holds the package back through the friction mounting thereof on the driven shaft. The shaft may be driven at constant speed or, if desired, it may be driven at variable speed which is controlled by the diameter of the package being wound so that the shaft speed is continuously or periodically reduced during the winding operation as the diameter of the package builds up. The friction driving connection between the shaft and the winding core heretofore used is of course subjected to wear and in the case where the shaft is driven at constant speed, the difference in speed between the core and shaft varies through a wide range during the winding operation. Such systems are prone to wear unevenly so that not only is an individual package subject to fluctuations in tension during the winding thereof but when a plurality of packages are simultaneously wound upon a plurality of cores driven by a common shaft, the various packages frequently show differences as a result of the variations in the friction systems connecting the common driving shaft with respective cores, the greatest deviations being attributable to differences in wear in several friction connections.

It is the primary object of the present invention to provide an improved drive connection between a driving shaft and a winding core which is characterized by a greatly reduced fluctuation in slippage whereby variations in tension of the tape during winding are minimized or eliminated.

An ancillary object of the present invention is to provide an improved system for winding a plu-

2

rality of tapes or the like simultaneously characterized in the production of a group of packages which are substantially identical in density and appearance.

5 A further object is to provide an improved winding system for producing a plurality of packages either one at a time or simultaneously which are substantially alike in appearance and density regardless of whether the drive system 10 for the winding shaft rotates such shaft at constant speed or at a varying speed depending upon the change in diameter of the package during winding.

Other objects and advantages of the invention 15 will be apparent from the drawing and the description thereof hereinafter.

In the drawing, which is illustrative of a preferred embodiment of the invention,

Figure 1 is an end elevation, somewhat diagrammatic, showing a preferred embodiment of the invention,

Figure 2 is a front elevation of the winding shaft driving systems on a somewhat enlarged scale,

25 Figure 3 is a still further enlarged view showing the interconnection between the friction drive and the winding core.

As shown in Figure 1, a wide sheet or film 20 is delivered from an unwinding roll 21 thereof 30 by means of a pair of nip feeding rolls 22 and 23, at least one of which is positively driven, preferably at constant speed. While the present invention is adapted to operate upon any strip or sheet of material, it is particularly useful for the slitting of a sheet carrying a coating on one 35 surface thereof of a pressure-sensitive adhesive and when such a material is handled, that one of the rolls 22 and 23 which bears against the pressure-sensitive adhesive coating is preferably ridged to reduce the area of contact. The sheet 20 then proceeds past the operating stage 24 which in the specific instance shown is a slitting operation. The sheet proceeds about a hard steel roll 25 with which one or more axially spaced slitter knives 26 mounted on a rotating

40 core 27 are provided for slitting the sheet into the desired number of narrower widths. The individual widths may be the same or, if desired, different widths may be slit from the sheet 20 by suitably spacing the knives 26. If 45 desired, the traction of the roll 25 may serve as the sole feeding device in which event rolls 22 and 23 may be omitted and in which case the roll 25 and the knives 26 are positively driven, 50 preferably at constant speed.

From the slitting operation 24, one group of alternate tapes 38 is drawn to a plurality of cores mounted on the driven shaft A and the intervening tapes 29 proceed to similar cores mounted on shaft B. Shafts A and B are driven at a speed in excess of the speed required to takeup the tapes which are delivered by the feeding means, such as the slitter system or feed rolls 22 and 23. For example, shafts A and B may be driven at a constant speed or at a speed varying with the diameter of the winding but in all cases at a sufficient rate to tension the tapes during their winding.

Each of the cores 3 is mounted upon a system comprising a magnetic element 7 which is mounted in fixed position on the driven shaft such as A and one or more magnetic elements, e. g. 4 and 5, rotatable on the shaft, there being a friction member, e. g. 11 or 12 interposed between the magnetic element 7 and the magnetic element or elements 4 and 5.

The magnetic elements may be made of any magnetic material, such as iron, steel or a magnetic alloy thereof. The element 7 and the elements 4 and 5 may be magnets, at least one of the magnetic elements must be a magnet, either permanent or an electromagnet. Preferably element 7 is a permanent magnet. As shown, the magnet 7 is secured in fixed position on the shaft A by means of the set screw 9 which engages in a keyway 10 of the shaft. The core 3, which may be of wood or cardboard, may be releasably held upon the outer periphery of the discs or plates 4 and 5 such as by means of the thin steel blades 6 which are set within recesses in the outer peripheries of the discs 4 and 5 and may have a short protruding portion for engaging the inner periphery of the core. The magnet 7 may be provided with annular grooves 8 in the opposite lateral faces thereof and friction rings 11 and 12 may be disposed in these grooves and project outwardly therefrom a short distance. The friction rings may be any suitable hard felt or any other material such as hard or soft metal capable of exerting a controllable friction between the discs 4 and 5 and the rings 11 and 12 respectively against which the rings bear. Instead of having complete rings 11 and 12 of felt or other friction material, there may be used instead a plurality of arcuate sections of a ring, such as three equi-angularly spaced, equally sized, arcuate sections secured in corresponding arranged complementary recesses within each lateral surface of the magnet.

This mounting unit so far described is the essence of the present invention. It should be noted that the frictional areas between the rings 11 and 12 and the plates 4 and 5 respectively are relatively small as compared to the available area that could be provided for frictional engagement between the magnet and magnetic element or elements. The magnetic coupling force is of prime importance and cooperates with the relatively small frictional forces to provide a drive coupling between the shaft and the core which is substantially free of fluctuations resulting from variations in the slippage along the friction areas. The friction rings 11 and 12 project out of the annular recesses 8 a predetermined small distance so that a strong magnetic coupling force is exerted between the magnet 7 and the elements 4 and 5, the magnetic coupling force preferably being greater than the frictional force.

Optionally, the following auxiliary means may

be provided for increasing both the frictional force and the magnetic coupling force between the drive shaft and the winding core. This auxiliary means may consist of a pair of yokes 13 and 14 disposed on opposite sides of the magnetic elements 4 and 5. The terminal ends of the yokes 13 and 14 are recessed as at 13a and these recesses receive friction plugs or pads 17 which project a small distance out of the surfaces of the yokes 13 and 14 and are adapted to bear against the outside lateral surfaces of the magnetic elements 4 and 5. The yokes 13 and 14 are provided at their lower ends with in-turned ears 13a and 14a respectively which are hinged upon a pin 15 secured in a fixed position in the rod or bar 16 by means of set screw 16a. The terminal ends 13b and 14b of the yokes 13 and 14 respectively are provided with internally threaded bores of opposite hand and within these bores the double ended screw 18 having threads of opposite hand is received. Midway of the screw 18 there is provided a knurled knob 19 rigidly secured by a set screw 19a so that rotation of the knob 19 either spreads the ends 13b and 14b apart or moves them closer together thereby either relieving or increasing the pressure of the plugs 17 against the magnetic elements 4 and 5. This increase in pressure tends to compress the friction rings 11 and 12, thereby reducing the space between the magnet 7 and magnetic elements 4 and 5 and increasing the magnetic coupling somewhat in addition to the effect of increasing the frictional force.

The use of the auxiliary means comprising the yokes 13 and 14 has the additional advantage of enabling the operator to make individual adjustments in the several winding core mounting systems upon any given driven shaft whereby differences in frictional or magnetic coupling forces may be compensated for in order to produce simultaneously a plurality of packages having substantially the same characteristics of density, size, and appearance.

The density of the felt friction rings 11 and 12 may be preselected to give any desired compressibility so that adjustment of yokes 13 and 14 can produce any desired variation in the magnetic coupling force as well as in the frictional coupling force between the driving shaft and the winding core or cores.

While the invention has been shown in connection particularly with an operation for slitting a wide sheet to a plurality of narrow widths which are wound up individually, the winding system of the present invention may be employed for the take-up of any strip of material whatsoever, regardless of its width, and regardless of the purpose of rewinding. For example, the rewinding may be solely for the purpose of converting a poorly shaped wound package to a uniformly shaped wound package or it may be for the purpose of drawing the strip or the like through a coating, humidifying, drying, or other treating operation or through a series of such treatments.

It is to be understood that changes and variations may be made without departing from the spirit and scope of the invention as defined in the appended claims.

70 I claim:

1. A winding machine comprising a driven shaft, an annular magnet secured concentrically to the shaft in fixed position for rotation therewith, a pair of annular magnetic members disposed rotatably on the shaft on opposite sides

of the magnet, annular grooves in the magnet disposed concentrically with respect to the shaft, friction rings disposed in said grooves and projecting outwardly therefrom a certain distance to provide frictional bearing surfaces against which the magnetic elements are held by the magnetic coupling force between the elements and the magnet, an annular winding core, and means for releasably securing said core to the outer peripheries of said magnetic elements.

2. A winding machine comprising a driving shaft, a core upon which a material is to be wound, magnetic and frictional coupling means between said shaft and core, said coupling means comprising at least two magnetic elements, at 15 least one thereof being a magnet, means for securing one of said elements to the shaft, means for securing another of said elements to the core, and a friction member disposed between said shaft element and said core element, and stationary means for applying pressure in an axial direction to the core element to adjustably urge the elements towards each other.

3. A winding machine as defined in claim 2 in which the adjustable means comprises at least one yoke straddling said shaft, a pivotal mounting for the yoke, said mounting having an axis at right angles to the axis of the shaft, and means for urging the yoke axially against the core element.

4. A winding machine comprising a driving shaft, a core upon which a material is to be wound, and magnetic and frictional coupling means between said shaft and core, said coupling means comprising at least two magnetic elements, at least one thereof being a magnet, means

for fixing one of said elements upon the shaft, and a friction member disposed between said magnet and another magnetic element, means for urging the magnet elements toward the magnet comprising a pair of yokes disposed on opposite sides of the elements and straddling the shaft, friction pads carried by the yokes and held by them against the magnet elements at areas on opposite sides of the shaft symmetrically disposed with respect to the shaft, said yokes being mounted on a common pivotal axis offset from the shaft and extending at right angles to a plane through the shaft, and screw means for swinging the yokes about said pivotal axis.

5. A winding machine as defined in claim 4 in which a plurality of other similar core supporting systems are mounted on said shaft for winding up a plurality of materials simultaneously, one on each of said cores, said machine comprising a bar offset from the shaft and extending approximately parallel thereto, a plurality of parallel pins mounted on said bar in fixed spaced positions along said bar to provide the pivotal axes of the respective pairs of yokes.
